UNITED STATES PATENT OFFICE.

BENIGNO GUERRERO, OF LOS ANGELES, CALIFORNIA.

ORANGE CLIPPER.

Application filed March 11, 1921. Serial No. 451,503.

To all whom it may concern:

Be it known that I, BENIGNO GUERRERO, a citizen of Mexico, residing at Los Angeles, in the county of Los Angeles and State of California, have invented new and useful Improvements in Orange Clippers, of which the following is a specification.

This invention relates to orange clippers.

An object of the invention is to provide an orange clipper having renewable cutting edges provided upon detachable blades which may be removed for the purpose of repair and replacement.

Another object of the invention is to provide a construction in orange clippers whereby the cutting knives may be made of different material than the other parts of the clipper to facilitate economical manufacture while permitting of using well tempered steel cutting edges.

A further object of the invention is to provide a construction in the clippers whereby the cutting edges of the blades of the jaws thereof, will slide over each other with a shearing action, and whereby the cutting edge of each blade may be caused to move against a shoulder on the opposite jaw to effect a pinching action, subsequent to the shearing action, so that in event the shearing action fails to cut the stem of the orange, the stem will be severed by the squeezing or pinching action.

Other objects will appear hereinafter.

The invention is illustrated in the accompanying drawings, in which:

Figure 1 is a view in perspective of the orange clipper.

Figure 2 is a view in section as seen on the line 2—2 of Figure 1.

Figure 3 is a view in perspective of one of the cutting jaws.

Figure 4 is a view in perspective of a removable blade adapted to be attached to the jaw shown in Figure 3.

Figure 5 is a view in perspective of the other cutting jaw.

Figure 6 is a view in perspective of a removable blade adapted to be secured to the jaw shown in Figure 5.

Figure 7 is an enlarged view in section as seen on the line 7—7 of Figure 1.

Figure 8 is a view in section as seen on the line 8—8 of Figure 1.

Figure 9 is a view in section as seen on the line 9—9 of Figure 1.

55

More specifically, 10 and 11 respectively indicate contiguous concave-convex jaws adapted to be advanced and retracted relative to one another to provide a shearing action after the manner common to clippers, 60

shears, and the like. These jaws are each formed integral with handles 12 and 13 respectively, which are of any suitable construction, material, and proportion, but here shown as being formed concave-convex with 65

the convex sides presented outermost to provide a smooth gripping surface, and formed by stamping to provide light weight, but rigid construction; the proportions being such that the handles jointly are easily 70

grasped and manipulated by the fingers and palm of the hand. Each of these handles are formed at the forward end with two sides members 14—14 and 15—15, formed integral therewith and separated by a space 75 16—16, one of these members 14 of each handle being extended to form the jaw. In assembling the clipper, each jaw is passed through the space 16, in the other handle and the jaws are pivoted together by means 80 of a pin 17, which extends through aligning holes 18, in each of the members 15 and 14 of each handle after the manner common to pliers and the like.

The handles are normally held yieldably 85 apart by a spring 19 to facilitate rapid movement of the jaws. Each handle is provided with adjustable hand guards 20 and

21, the upper guard 20 extending contiguous with the handle a short distance and turning 90 upward in an arcuate path to conform to the portion of the hand between the thumb and forefinger, the lower guard is disposed obliquely across the handle and is adapted to

extend between the first and second fingers 95 of the hand when the handles are gripped in the palm of the hand.

These guards are provided with clips 22, bent to slidably engage the handles, as shown

in Figure 9, so that the guards may be moved 100 to various positions longitudinally of the handle and thereby be disposed to fit the hand of the operator.

The renewable blades *a—b* are particularly shown in Figures 4 and 6, the blade shown 105 in Figure 4 being shaped to conform with

the jaw 10 and the blade shown in Figure 6 being shaped to conform with the other jaw 11. Each blade *a* and *b* embodying a plate portion *c* adapted to seat on the inner face of the side member 14, has an opening *d* through which the pivot pin 17 extends. The manner in which these blades are disposed upon the respective jaws is shown in Figures 7 and 8.

10 It will be observed that the blade fixed to the jaw 10, protrudes forward thereof and is formed with a cutting edge of acute angle, whereas, the blade secured to the jaw 11 is disposed thereon, so that it also protrudes 15 beyond the jaw and is formed convex on the outer side. Each blade is secured to the inner face of its respective jaw by a rivet or screw 23, so that when the jaws are brought together the blades slide over each other to 20 give the proper shearing action.

As a means for effecting a pinching action subsequent to the shearing action, shoulders 24 and 25 are formed on the jaw members a short distance rearward of the 25 cutting edges of the blades against which the cutting edges close, as indicated in dotted lines in Figure 7, after the blades have assumed their overlapping position. By this construction severance of the stem of the 30 orange being acted on will be insured, as in event the shear fails to cut the fibers the latter will be pinched between the blades and shoulders and thereby be completely severed.

The plate portions *c* of the blades are also 35 formed to extend rearward contiguous with the handles a short distance and terminate in angularly disposed projections 26 and 27 respectively, which when the blades are secured in place extend inwardly toward one 40 another to form a means for holding the coil spring 19; the projections extending into the end coils of the spring.

The operation of the shears is apparent 45 from the foregoing, it being seen that when the jaws are brought together the cutting edges of the blades will pass each other with a shearing action and will be brought against the shoulders 24 and 25, as indicated by the dotted lines in Figure 7; the shoulders 50 limiting the movement of the jaws relative to one another to prevent jamming and also providing a pinching effect as before described.

When the blades become dull or worn 55 they may be readily removed for sharpening or replacement, it being only necessary to renew the blades when the cutting edges of the clippers are excessively worn, thus obviating renewing the complete tool.

60 By forming the jaws and blades concave-convex, the stem of the fruit may be cut so close to the surface of the fruit as not to project therefrom a sufficient distance to injure adjacent fruit in packing, as the convex curvature of the blade when positioned

against the portion of the fruit adjacent the stem will permit the blade on closing of the jaws to advance slightly into the depression or recess in the fruit from which the stem projects. For this purpose the blades and the jaws are constructed comparatively small and of quite pronounced concave-convex form, as particularly shown in Figure 8.

While I have shown and described a specific embodiment of my invention, I do not 75 limit myself to the exact details of construction or arrangement of parts shown, but may employ such other changes and modifications as come within the spirit of the invention, without departing from the 80 scope of the appended claims.

I claim:

1. In an orange clipper, a handle, a grip guard projecting outwardly from said handle having a portion bent around the 85 handle in slidable engagement therewith whereby the guard may be moved longitudinally on the handle to fit the hand of the operator.

2. In an orange clipper, a pair of handles, 90 a pivot pin connecting said handles, each of said handles embodying a pair of spaced side members one of which terminates adjacent the pivot and the other being extended to form a jaw, the two side members 95 of one of said handles extending through the space between the side members of the other handle, and a detachable blade secured to the jaw.

3. In an orange clipper, a pair of handles, 100 a pivot pin connecting said handles, each of said handles embodying a pair of spaced side members one of which terminates adjacent the pivot and the other being extended to form a jaw, the two side members of one of 105 said handles extending through the space between the side members of the other handle, a detachable blade for the jaw, and a rivet connecting the blade to the jaw.

4. In an orange clipper, a pair of handles, 110 a pivot pin connecting said handles, each of said handles embodying a pair of spaced side members one of which terminates adjacent the pivot and the other being extended to form a jaw, the two side members of 115 one of said handles extending through the space between the side members of the other handle, a detachable blade comprising a plate portion seating on the inner face of the wall of the handle on which a jaw is formed 120 having an opening therein through which the pivot pin extends and embodying a blade substantially conforming to the jaw having a cutting edge projecting beyond the edge of the jaw.

5. In an orange clipper, a pair of handles, 125 a pivot pin connecting said handles, each of said handles embodying a pair of spaced side members one of which terminates adjacent the pivot and the other being extend-

ed to form a jaw, the two side members of one of said handles extending through the space between the side members of the other handle, a detachable blade comprising a 5 plate portion seating on the inner face of the wall of the handle on which a jaw is formed having an opening therein through which the pivot pin extends and embodying a blade

substantially conforming to the jaw having a cutting edge projecting beyond the edge of 10 the jaw; said plate portions of the blades being formed on their inner end portions with projections, and a coil spring having its end coils engaged by said projections.

BENIGNO GUERRERO.
